UNITED STATES PATENT OFFICE.

WINTHROP K. HOWE, OF ROCHESTER, NEW YORK, ASSIGNOR TO GENERAL RAILWAY SIGNAL COMPANY, OF GATES, NEW YORK, A CORPORATION OF NEW YORK.

TRAIN CONTROL.

Application filed February 25, 1922. Serial No. 539,218.

This invention relates to automatic train control systems for railroads.

In the practical application of train control systems to railways, it is desirable to make provision such that the locomotives, or other vehicles equipped, may run either pilot first, or tender first, over the railroad in the normal direction of traffic, and be in either case under proper control. Similarly, provision should be made to permit a vehicle equipped with train control apparatus to travel over the railroad in a direction opposite to the normal direction of traffic for which the railroad is signalled, and while so traveling against the normal direction of traffic, be allowed to proceed without unnecessary imposition of control, since the vehicle in this case automatically puts to stop the signals ahead of it and places the track-way devices of the train control system in their active stopping condition. A still further requisite is that the arrangement for communicating controlling influences from the trackway to the moving vehicle should be adaptable to single track operation, as well as double track operation, with the minimum amount of expense or complication.

Briefly stated, the primary object of the present invention is to devise a simple arrangement of cooperating devices on the trackway and on a vehicle, which permits the communication of the desired controlling influences for governing cab signal or train control mechanism when the vehicle is traveling over the track in the normal direction of traffic, regardless of which end of the vehicle is leading, which will not act to communicate such influences when the vehicle travels over the track either end ahead in a direction opposite to the normal direction of traffic, and which is susceptible of adaptation for single track operation.

Various other objects, characteristic features, and advantages of the invention will appear hereinafter as the description progresses.

In the accompanying drawings, Figure 1 shows in a simplified and conventional manner a portion of double track equipped in accordance with this invention;

Fig. 2 illustrates in a simplified and diagrammatic way one typical form of a signaling system for single track railroads, conveniently termed an absolute-permissive-block system, and shows the application of

the track devices of the train control system to this type of block signal system;

Fig. 3 illustrates in a simplified and conventional manner one form of car apparatus with a view of the track element, the parts being illustrated more with the idea of making it easy to understand their functions and mode of operation, rather than with the purpose of showing detail construction and arrangement preferably employed in practice;

Fig. 4 is a diagrammatic view showing the modification of the car equipment shown in Fig. 3 to provide an automatic stop system.

Referring first to the trackway equipment for double track shown in Fig. 1, the track rails 1 are bonded together in the usual way by bond wires and channel pins, or the like; and these track rails are divided into blocks of the desired length by insulated joints 2 in conformity with recognized block signal practice, only one block E with the portions of adjacent blocks D and F being shown. Since the devices and circuits associated with these blocks are the same, for convenience they will be given the same reference characters with distinctive exponents. Each block is equipped with a normally closed track circuit of the usual and well-known construction, comprising a track battery 3 and a track relay 4, with the usual adjuncts, such as limiting resistance, battery chutes, relay boxes, and the like, all as commonly used in practice.

It is contemplated that the train control system will be used as a supplement or an adjunct to some suitable type of automatic or auto-manual block signal system, including fixed track signals of the semaphore, color light, or other type. The various forms of the signals, control circuits, and relays suitable for this purpose are now well-recognized in the art; and to avoid useless complication, semaphore signals 5 at the entrance to each block have been shown conventionally, without any attempt to illustrate their well-known structure and control circuits, it being understood that these signals will give the usual clear, caution, and stop indications, dependent upon the presence or absence of trains in the corresponding block and in the next block in advance. The adaptability of the train control system of this invention to block signal systems of other types, employing other types of track-

way signals or other forms of control circuits, is considered to be so evident as to require no specific illustration or description.

- 5 The train control system of this invention in its simplest form, which has been selected for the purpose of explaining the nature of the invention, requires the communication of a stopping impulse or influence from the 10 trackway to each passing vehicle at each caution signal, with or without a similar stopping impulse at each stop or danger signal; and for this purpose there is located adjacent to the entrance end of each block 15 (traffic being from left to right as indicated by the arrow) a track element or inductor T, which may be disposed a short distance in the rear of the insulated joints 2 defining the entrance to the block in question, or opposite such joints, or a distance 20 in advance thereof, depending upon the type of control circuits for these track elements. In the particular arrangement of control circuits shown, track element T is located a short distance in the rear of the insulated joints 25 at the entrance of the corresponding block, and the controlling condition of said track element is governed by a line relay 6 that is controlled by the track relays of the corresponding block and the next block in 30 advance, as clearly shown on the drawing. It is noted here that the various circuits are shown in a conventional manner with the reference character B indicating a connection directly to one terminal of a battery or other source of current and the reference character C or N indicating a direct connection to the other terminal of the same source, it being understood that several batteries or 35 other sources of the appropriate voltage and current capacity may be used in the respective circuits in conformity with engineering practice.

40 The track element or inductor T comprises in general a U-shaped core or yoke 7 of soft iron laminations, a coil or winding 8 on said core, together with a suitable support or mounting for housing and protecting said core and coil which may take various forms 45 and which for simplicity, is not shown. The coil 7 is provided with enlarged pole pieces which are disposed a considerable distance above the top of the track rails and outside one of the rails. In one specific arrangement, the track inductors are located with 50 their pole pieces about $2\frac{1}{2}$ " above the level of the top of the running rails and with their center lines about 19" outside of one or the other of the running rails. The coil 55 8 of the track inductor T is connected through a front contact 9 of the corresponding line relay 6, and thus is in a closed circuit of low resistance when said line relay is energized.

60 Referring to Fig. 3, the car equipment

comprises two car elements or receivers L and L^a carried on opposite sides of the locomotive or other vehicle, directly opposite each other as shown, or in staggered relation. These car elements are in practice 70 housed and protected, spring supported, or otherwise mounted, preferably on a truck, side frame, or similar part having a fixed relation to the track rails, the specific structure of this support and housing, however, 75 forming no part of the present invention. Each car element or receiver L—L^a consists of a U-shaped core or yoke 10 of soft iron laminations and having enlarged pole pieces, said cores being similar in size to the 80 cores of the track elements and being carried on the vehicle so as to come directly over said track elements. On one leg of the core 10 is a primary or exciting coil P and on the other leg is a secondary or receiving coil 85 S. These coils of the two car elements L—L^a on opposite sides of the vehicle, are preferably placed on the respective legs in such a way that the primary or exciting coil P is ahead or leading and first encounters the 90 track inductors T as the vehicle travels in the normal direction of traffic with its alternate ends leading. For example, if the track elements T, which in accordance with this invention for double track railroads are located all on the same side of the track, are on the righthand side of the track with respect to the normal direction of traffic, as shown in Fig. 1, then the primary coils P—P^a of the two car elements L—L^a are 95 disposed as shown in Fig. 3, with the primary coil on the righthand side of the vehicle leading as the vehicle travels in the 100 normal direction of traffic.

105 In connection with this invention, there is employed a circuit controlling device which automatically shifts on changes as the vehicle changes its direction of travel. While such circuit controlling means may be coupled to and operated by the reversing 110 lever or controller by which the direction of movement of the vehicle is selected, it is preferred to actuate this automatic circuit controlling means directly from the car axle, because, among other things, the desired selection is set up automatically and can not exist unless the movement of the vehicle corresponds, something which is not necessarily true in the case of the reversing lever of a locomotive or the reversing handle of the controller of an electrically propelled car. In the simplified construction of this circuit controller, conveniently termed a reversing switch, a sleeve or collar 11 is mounted on one of the vehicle axles and provided with suitable bearings to turn thereon. This collar 11 is provided with a friction member or brake shoe 12 pressed against the axle by a spring 13, so that said collar 11 is frictionally driven in one direction or 115 120 125 130

the other depending upon the direction of rotation of said car axle. The collar 11 opens and closes certain contacts alternately, and in the simplified construction shown, a 5 radially extending arm integral with said collar 11 carries an insulated contact strip 14 arranged to connect brushes 15 and 16 alternately with a brush 17, the length of the strip 14 and the spacing of said brushes 10 being such that a connection between brushes 16-17 is made before the connection between brushes 15-17 is broken; and vice versa. That is, this contact strip 14 is of such a 15 length that the circuit controlling device 15 constitutes a switch of the make-before-break type. These brushes or contact fingers 15-16 and 17 are shown conventionally and are assumed to be suitably supported upon a panel of insulating material, said panel 20 also supporting fixed stop members 18 limiting the extent of movement of the collar 11.

The control impulse or influence communicated from the trackway to the moving vehicles in accordance with this invention may 25 be utilized in various ways for the automatic regulation of the movement of the vehicle, ordinarily by operating some suitable form of brake control mechanism. It is contemplated that such brake control 30 mechanism will act upon the air brake system now commonly in use, and in some one of the well-known ways, cause an automatic brake application in the proper manner, suitable provisions being made for preventing 35 the engineer from recharging and releasing, for producing a limited reduction in brake pipe pressure and otherwise producing a braking effect in accordance with accepted air brake practice. The specific character 40 of the brake control apparatus, and its governing mechanism, forms no part of the present invention, which is adaptable in a manner that will be evident to those skilled in the art, to any one of the various types 45 or kinds of brake or power control devices, dependent upon speed or other concurrent conditions; and to simplify the disclosure of the present invention, a brake control apparatus, capable of performing the desired 50 functions, is illustrated conventionally and designated K. And it should be understood that this device K is one which when deenergized, produces a brake application or other desired control, and is inactive when 55 energized. To conform with the particular type of control circuits shown in Fig. 3, this device K has associated therewith contacts, shown conventionally as an insulated disc 19 and arrows, which are normally 60 closed, that is, while said device K is energized, and which are automatically opened when said device is deenergized.

A suitable electro-responsive device, electrically connected to the receiving coil S or 65 S^a of the active car element, and responsive

to the influence produced upon said car element by a track element in the active stopping condition, is employed for governing the device K. While said electro-responsive means, or translating device, may take various forms, in Fig. 3 there are shown a main control relay G, and a repeater relay R. In practice, these relays are constructed and mounted so as not to be improperly operated by the shocks, jars, and vibrations to which 70 they are subjected, and have their structural and electrical characteristics adapted to their respective duties. The main control relay G has an armature and contact finger shown conventionally which is pivotally supported at its center of mass and is rocked about its pivotal axis in one direction by a spring and is attracted in the other direction when the relay is energized, said contact finger 20 75 cooperating with two normally closed front contacts shown conventionally as arrows. The repeater relay R is provided with a similar balanced armature 21 having a front and a back contact, as shown.

The type of car equipment shown in Fig. 3 80 is designed to provide what may be termed an auto-manual, permissive, or semi-automatic system, that is, a system in which the brakes are automatically applied at each caution signal unless the engineer takes appropriate action in recognition or acknowledgement of such signal. For this purpose a hold-by or acknowledging contactor A. C. is provided. In the simplified form shown, this acknowledging contactor comprises a 85 plunger 22, with a suitable knob for facilitating its manual manipulation, which is urged upward by a spring 23 between a collar on said plunger and a guide therefor. This plunger 22, when depressed in opposition to the spring 23, forces a spring contact finger 24 into engagement with a stationary contact, indicated conventionally as an arrow. At the same time, another contact finger 25 is released and is moved downward by a tension spring 26 at a rate determined by a suitable dash-pot or timing mechanism 27. The contact finger 25 is provided with a resilient spring and stop which cooperates 90 with a stationary contact, shown as an arrow, in such a way, that when said finger 25 attains a predetermined lower position, said spring engages its stop and is pulled out of contact with the stationary contact. Generally speaking, the acknowledging contactor A. C. consists of normally open contacts 24, which are closed when said contactor is actuated, and normally closed contacts 25 which are automatically opened if the contactor is held in its operated position 95 longer than a predetermined time.

Since actuation of the acknowledging contactor A. C. serves to avoid an automatic brake application, as explained hereinafter, it is considered desirable for some situations 100

to have a record showing the time of each operation of said acknowledging contactor by the engineer, so that when desired, in case of accident or otherwise, it can be determined whether or not the automatic brake applying mechanism was rendered ineffective by the engineer. To satisfy this requirement, a suitable time recording device is associated with and actuated by the plunger 22, a record being made each time said contactor is actuated. Since various forms of recording mechanisms, including clock-work devices, dials and tape, or the like, adaptable for this purpose, are well-known in the art, such recording mechanism 28 is shown diagrammatically, and is illustrated as being provided with a lever or arm 28¹ arranged to be actuated by the downward movement of the plunger 22, so that a record, giving the hour and minute, is made each time said plunger is depressed.

In connection with the specific type of car equipment shown in Fig. 3, a reset switch R. S. is employed. This reset switch R. S. is preferably located so that it is accessible only from the ground and consequently can not be operated until the train is brought to a stop or is sealed or in some other suitable manner protected such that its operation involves considerable annoyance, publicity, or the like, the purpose being to establish a penalty in connection with the operation of the reset switch R. S., as contrasted with the simple manipulation of the acknowledging contactor A. C., so that the engineer will watch out for the signal indications and actuate said acknowledging contactor in preference to being obliged to work the reset switch R. S. This reset switch R. S., shown in simplified form, comprises a spring push button or switch blade 29, having normally open and normally closed contacts.

Operation.—Normally, when the vehicle is traveling between control points under clear traffic conditions, parts and circuits of the car equipment are in the condition shown in Fig. 3. It is assumed that the vehicle is headed in the direction of the arrow. The collar 11 of the automatic reversing switch, 50 is driven by the car axle to the upper extreme position against the upper stop 18 as shown, establishing an electrical connection between the contact fingers 15—17 and breaking the connection between the fingers 55 16—17. The primary or exciting coils P and P^a of the two car elements L—L^a are each energized from a suitable source of current preferably a storage battery by a circuit which may be traced as follows: commencing at B, front contact and armature 21 of repeater relay R, wires 30 and 31, switch blade 29 of reset switch R. S. and its normally closed contact, wire 32, normally closed contacts 25 of the acknowledging contactor A. C. wire 33, device K, wire 34, pri-

mary coil P^a, wire 35, primary coil P, and thence to N.

Main control relay G is connected in circuit with the secondary coil S as follows: commencing at B, armature 20 of relay G, 70 and its front contact, wires 36 and 37, brush 17, contact 14, brush 15, wire 38, secondary coil S, wires 39 and 40, relay G to N. This energizing circuit for the relay G includes a front contact of the relay itself, making it a 75 stick relay.

The repeater relay R is directly energized through the other front contact of the relay G by a circuit which may be traced as follows: commencing at B, armature 20 and 80 front contact, wire 41, relay R to N.

From the foregoing circuits it will be noted that the device K is normally maintained energized, and is deenergized when the front contact of repeater relay R opens, 85 or the normally closed contacts 25 of the acknowledging contactor open or the reset switch R. S. is operated. Also, the device K is connected in series with the primary or exciting coils P—P^a, so that the flow of 90 current through these coils is checked and if it falls too low for safe and reliable operation, the device K will be operated.

The primary coil P, being constantly energized, tends to send flux through the core 95 10 of the car element L, but on account of the relatively large air gap between the pole pieces of said core, the partial magnetic circuit for said flux is of relatively high reluctance, and comparatively little 100 flux passes through the secondary coil S. Such flux as may be threading the coil S, being steady, does not affect the current through the main control relay G.

Suppose now that the vehicle approaches 105 a track element T in its active stopping condition, that is, with its coil 8 in open circuit. The track element in this stopping condition constitutes in effect an inert mass of iron affording a magnetic bridge or loop 110 for the core 10 of the car element. As the car element passes over the track element, the reluctance of the magnetic circuit through the primary and secondary coils P and S is first decreased from normal to a 115 minimum and then increased from a minimum back to normal. By virtue of such change in reluctance, partly aided by diversion of flux from leakage paths around the primary coil P, there is a quick change of flux through the secondary coil S, first an increase, and then a decrease. This change of flux, in accordance with well-known principles induces a voltage in the secondary coil S which is in effect one cycle of alternating current, usually of the distorted wave form. This induced voltage (either the first or second wave, depending upon the connections,) opposes the battery or other source supplying the energizing cur- 125 130

rent for the main control relay G, thereby reducing such current to the point where the armature of said relay is retracted. It may be noted here that the connections are preferably made such that the relay operates on the first wave or half-cycle. The relay G, being a stick relay, maintains its contacts open, after the slightest opening thereof, and while the induced voltage in the secondary coil is of momentary duration, the relay G opens its contacts and keeps them open until otherwise restored. The dropping of relay G causes the relay R to drop.

Assume that the engineer was alert and observed the signal indication prior to the movement of the vehicle past the track element in the stopping condition just considered, and that the engineer, just before passing the track element, presses down the plunger 22 of the acknowledging contactor A. C. so that the engineer is obliged to close the reset switch R. S., in order to restore the relays G and R, reenergize the device K, and proceed. Since the operation of the reset switch R. S. is attended with some difficulty, as previously explained, it is thought that the engineer naturally taking the easiest course, will prefer, and, as a practical proposition, be really forced to be alert and watch out for the signal indications, in order that he may avoid the penalty associated with operation of the reset switch by making the appropriate and timely movement of the acknowledging contactor.

In order to frustrate any attempt upon the part of the engineer to defeat the objects of the system by fastening down the acknowledging contactor A. C. the time controlled contacts 25 are provided, and these act to interrupt the energizing circuit for the device K in the event that the plunger 22 is fastened down, or is carelessly held down for more than a predetermined time for which the dash-pot or timing device 27 is adjusted. The time for the opening of the normally closed contact 25 is preferably made long enough to give the engineer all reasonable latitude in passing a signal, but too short to permit him to pass two signals in succession by one manipulation. If necessary, the engineer may operate the acknowledging contactor several times in succession, in case he, misjudging his speed or distance to the signal, should operate the acknowledging contactor too quickly. Similarly, the reset switch R. S. is protected so that it can not be fastened down. It will be noted that when the reset switch blade 29 is shifted, the circuit for energizing the device K is broken at its normally closed contacts; and consequently, while the relays G and R can be restored to normal by operating the switch 29, the device K is not energized until said switch is restored to the normal position. Hence, the reset switch R. S. can not be carelessly left or fastened in the wrong position, otherwise the device K is deenergized and the train can not proceed except under such restrictions as may be imposed by the device K.

Thus, the engineer, by making a timely operation of the acknowledging contactor A. C. may prevent deenergization of the device K and immediately restore the relays G and R, putting all of the apparatus back in the normal condition, so that after the car element has passed beyond the influence of the track element, the plunger 22 may be released.

Suppose now that the engineer being asleep, incapacitated or for some other reason fails to observe or correctly interpret the signal indication, fails to operate the acknowledging contactor before passing the track element in its active stopping condition. Then when the repeater relay R drops, it breaks the normally closed energizing circuit for the device K, causing said device to be set into operation to apply the brakes or impose some other train control restrictions. When the device K operates, its contacts 19 open, thereby preventing restoration of the relay G by manipulation

of the acknowledging contactor A. C. so that the engineer is obliged to close the reset switch R. S., in order to restore the relays G and R, reenergize the device K, and proceed. Since the operation of the reset switch R. S. is attended with some difficulty, as previously explained, it is thought that the engineer naturally taking the easiest course, will prefer, and, as a practical proposition, be really forced to be alert and watch out for the signal indications, in order that he may avoid the penalty associated with operation of the reset switch by making the appropriate and timely movement of the acknowledging contactor.

In order to frustrate any attempt upon the part of the engineer to defeat the objects of the system by fastening down the acknowledging contactor A. C. the time controlled contacts 25 are provided, and these act to interrupt the energizing circuit for the device K in the event that the plunger 22 is fastened down, or is carelessly held down for more than a predetermined time for which the dash-pot or timing device 27 is adjusted. The time for the opening of the normally closed contact 25 is preferably made long enough to give the engineer all reasonable latitude in passing a signal, but too short to permit him to pass two signals in succession by one manipulation. If necessary, the engineer may operate the acknowledging contactor several times in succession, in case he, misjudging his speed or distance to the signal, should operate the acknowledging contactor too quickly. Similarly, the reset switch R. S. is protected so that it can not be fastened down. It will be noted that when the reset switch blade 29 is shifted, the circuit for energizing the device K is broken at its normally closed contacts; and consequently, while the relays G and R can be restored to normal by operating the switch 29, the device K is not energized until said switch is restored to the normal position. Hence, the reset switch R. S. can not be carelessly left or fastened in the wrong position, otherwise the device K is deenergized and the train can not proceed except under such restrictions as may be imposed by the device K.

If the coil 8 of a track element or inductor T is included in a closed circuit of low resistance or virtually short-circuited, at the time the vehicle passes it, then there is not induced in the secondary coil S sufficient voltage to cause operation of the relay G. This may be explained on the theory that the coil 8 of the track element acts as a choke coil and opposes or chokes back the passage of flux through the core 7 of the track inductor, thereby preventing the rapid change of flux through the secondary coil S to the same degree as when the coil 8 is open-circuited.

If the car should be turned end for end, and should travel in the same normal direction of traffic, the other car-carried element or receiver L^a will be on the right hand side of the track where the track elements T are located. At the same time, the collar 11 of the automatic reversing switch is shifted by the change in the direction of rotation of the car axle, so as to connect the relay G to the secondary coil S^a (through a circuit which may be readily traced from analogy to the one for secondary coil S) rather than to the secondary coil S . In other words, as the car changes end for end, the car elements on the opposite sides thereof are alternately rendered effective, and conditions are automatically set up for the cooperation of an active car element with the track elements. In this connection, it should be remembered that the track elements T will all be located on one side of the track, the righthand side as shown, with respect to the normal direction of traffic.

Occasionally locomotives or whole trains are obliged to run opposite to the normal direction of traffic. In this case, it will be evident that the train will put the track elements ahead of it in the active stopping condition, since it occupies itself in succession the track circuits controlling these elements before it reaches them. Consequently, unless some special provision is made, a train traveling opposite to the normal current of traffic would be continuously stopping itself. Such against traffic movements, being abnormal and made only under special orders and in conformity with the rules, do not require the protection of an automatic train control system. Referring to Fig. 3, assume that the vehicle headed as shown, should reverse its movement and back up opposite to the direction of traffic. It will be evident that the collar 11 of the automatic reversing switch will be shifted as the direction of rotation of the car axle is reversed, rendering the lefthand element L^a active and the righthand element L inactive; and since the track elements will pass under the element L , as the train makes this against traffic movement, no influence will be communicated. The same is true in case the vehicle is headed in the opposite direction.

The car equipment shown in Fig. 3, as previously stated, is designed for imposing a permissive or auto-manual brake control but the same principles and functions underlying this invention can, of course, be employed to exert an absolute control. Fig. 4 illustrates how the circuits of Fig. 3 are modified to provide such absolute control. In this arrangement, the acknowledging contactor $A. C.$ is omitted. The main control relay G has the same stick circuit as in Fig. 3, but is picked up or restored directly

through the open contact of the reset switch $R. S.$, wire 47 to wire 37, and thence through the relay G the same as in the pick-up circuit previously traced. The train control device K is deenergized and set into operation when the repeater relay R opens. It will be observed that in this arrangement of circuits, train control device K is operated, independently of any action upon the part of the engineer, whenever the relays G and R are deenergized, and that after such deenergization, the parts must be restored by manipulation of the reset switch $R. S.$ It should be understood that this car equipment of Fig. 4 may be employed with an overlap system, and the train control device K be one which automatically applies the brakes independently of speed or other concurrent conditions; or this arrangement may be used to enforce obedience to a caution signal, provided the train control device K is suitably constructed so as to make the brake application dependent upon speed, location of the vehicle in the block, or other conditions consistent with the automatic control of vehicles in caution blocks.

This invention also provides an organization permitting the vehicle to travel over single track railroads as well as double track railroads. From the foregoing explanation, more particularly in connection with Fig. 3, it will be observed that the car equipment is such that, regardless of which end of the vehicle is ahead, it will receive control from track elements on one side of the track, for example, the righthand side. If, therefore, the track elements on single track railroads are located on the righthand side of the track with respect to the direction in which the vehicle is traveling, and with respect to the direction of traffic governed by the signals for such vehicle, the vehicle, equipped in the same way as for double track operation, may travel over a single track and be under the appropriate control.

In single track operation signal protection should be provided for train movement in either direction, that is, protection for trains traveling toward each other (opposing moves), and for trains traveling in the same direction as on double track railroads (following moves). These and other requirements for single track operation are satisfied, so far as signal indication is concerned, in a thoroughly practical manner by the type of block signal system now in common use and known as an absolute-permissive-block system; and while the train control system of this invention may be applied to other types of single track block signal systems, this A. P. B. system has been selected to illustrate the adaptability of the invention to single track railroads. The arrangement of signals, their control circuits, and mode of operation of the A. P. B. sys-

tem is fully disclosed, for example, in the patent to Wight, 1,294,736, Feb. 18, 1919; and in view of the complete disclosure in said patent, no attempt will be made to describe the A. P. B. system in detail, and the application of the train control system of this invention will be explained simply and briefly.

Fig. 2 illustrates one arrangement of signals for an A. P. B. system. The stretch of single track, shown by a single heavy line between two passing sidings X is divided into track sections a , b , c , etc., in the usual way. Signals, designated Y^1 to Y^8 , are located at intervals along this stretch of single track, these signals being shown located oppositely to each other in pairs. The two signals Y^2 and Y^7 at each end of the stretch of single track, and governing train movement into the stretch, are known as the absolute or starting signals, and in practice are made distinguishable, by the shape of the blade, marker lights, or the like, from the intermediate signals Y^3 to Y^6 . The starting signals Y^2 and Y^7 , when in the stop position are interpreted to signify "stop and stay". The intermediate signals Y^3 to Y^6 are of the permissive type, and when in the stop position, signify that the train may pass them after complying with the prescribed rules, expecting to find another train or other obstruction ahead.

Without pointing out in detail the relays and control circuits involved, since this is fully explained in the patent above mentioned, the general scheme of operation of the A. P. B. system is as follows. When a train enters the stretch of single track from either end, say the left-hand end as shown in Fig. 2, it causes all of the opposing signals Y^3 , Y^6 and Y^7 to assume the stop position, thereby blocking all train movement in the opposite direction. As this train travels through the stretch of single track, these opposing signals are held in the stop position until the rear end of the train has successively passed them. The signals Y^2 , Y^4 and Y^6 , governing traffic in the same direction in which the train in question is running, are caused to assume in turn, the stop, caution, and clear positions, the same as in double track block signal systems.

In applying the train control system of this invention to the A. P. B. system shown in Fig. 2, a track element T^1 , T^2 , etc., is located at each signal, on the righthand side of the track with respect to the direction of traffic governed by the respective signals, and the control circuit for each track element is closed when corresponding signal is in the clear position, and opened when that signal is in the caution or stop position. This desired control of the track elements may be obtained from a circuit controller 48 operated by the signal itself, as

shown in Fig. 2 in connection with the signal Y^4 , said circuit controller being shown in accordance with established convention, and being closed only when the signal Y^4 is in the clear position. Or, the control circuit for the track element may be governed by any other circuit controlling means responsive to a change in the signal indication from clear to caution, or to stop. For example, the control circuit for the track element may be taken through neutral and polar contacts 49 and 50 of the line relay 51 which is associated with each signal in the A. P. B. system, as pointed out in the patent above mentioned, such arrangement being shown in Fig. 2 in connection with the signal Y^6 .

From the foregoing explanation it will be appreciated that, regardless of which end of the vehicle is ahead, and regardless of the direction in which it is traveling when it enters a stretch of single track, the car element on the right-hand side of the vehicle will be the one which is active, and will be the one cooperating with the track elements having their controlling condition dependent upon traffic conditions in advance of the vehicle. If there is a train in the same stretch of track traveling in the opposite direction, these track elements are in the stopping condition. If there is a train in the stretch of single track traveling in the same direction as the train in question, these track elements will be in the clear inactive condition, or in the active stopping condition, depending upon the proximity of said train ahead. It will further be noted that if a train, after having entered the stretch of single track traveling in one direction, reverses its direction of movement, the change in the direction of rotation of its car axle automatically shifts the control of its train control device K to the other car element, placing such train under the control of those track elements governing traffic in the direction the vehicle has now assumed. In short, regardless of which end of the vehicle is ahead, and its direction of movement on the stretch of single track, it is always under the proper control; and the same vehicle, when passing on to the double track, will be placed under proper control, so long as it travels in the normal direction of traffic for which said double track is signalled, regardless of which end of the vehicle is ahead, such control being automatically removed if the vehicle travels against the normal current of traffic.

While various specific constructions and arrangements of parts and circuits for practicing the invention have been shown and described, and the mode of operation and characteristic features of the invention pointed out, it should be understood that this disclosure does not exhaust all possible modifi-

cations, adaptations, and embodiments of means constituting the invention, nor does it include the various devices and methods of signal or train operation well-recognized in the art and commonly practiced. The specific type of inductive communicating means is merely illustrative, and being disclosed and claimed in other applications, no claim is made herein to combinations and sub-combinations of the impulse communicating means, per se, the present invention involving the application and combination of such means with an automatic reversing switch, or equivalent, to take care of the various train movements found in practice and previously explained.

What I claim is:

1. In a train control system, in combination with a section of single track having signals for governing traffic in both directions, an inductive track influence communicating device at each signal governed in accordance with the indication thereof, car equipment comprising duplicate inductive receiving means on opposite sides of the car adapted to be inductively influenced through an intervening air gap by said trackway devices, and automatic means operated in accordance with the direction of rotation of a car axle and including a frictional device for rendering effective the receiving means on the side of the car corresponding to those trackway devices for governing traffic in the direction in which the car is traveling.
2. In a train control system, in combination with a single track territory having double track meeting points, two groups of signals in said single track territory, each group governing traffic in one direction, each group of signals giving the usual clear, caution and danger indications to a train traveling in one direction due to traffic ahead in the same block or in the next block in advance traveling in the same direction, and giving a stop indication to said train due to a train ahead traveling in the opposite direction, two groups of inductive trackway influence communicating devices governed respectively by said groups of signals, two car-carried inductive receiving devices arranged to cooperate respectively with said groups of trackway communicating devices and to receive influences from said trackway devices through an intervening air gap, car-carried control equipment for controlling the vehicle brakes in accordance with the influences received and car-carried means for connecting one or the other of said receiving devices to said control equipment in accordance with the direction of rotation of a car axle, whereby said car-carried control equipment is governed by the influences from said group of trackway communicating devices which is controlled in accordance with traffic conditions ahead in the direction of movement

of the car in single track or double track territory, irrespective of which end of the car is ahead.

3. In an automatic train control system, the combination with a stretch of track having traffic controlled influence communicating devices on one side of the center line of the track rails with respect to the normal direction of traffic, car equipment comprising receiving devices located on both sides of the center line of the vehicle, a coil on each of said receiving devices, a circuit including the winding and the front contact of a stick relay and a source of uni-directional voltage, and a reversing switch, operated in accordance with the direction of rotation of a car axle, for selectively connecting the coil on one or the other of said receiving devices in series with said circuit in accordance with the direction in which the vehicle is traveling.

4. In an automatic train control system, in combination, a stretch of track having traffic controlled influence communicating devices comprising inert non-magnetized bodies of iron when in their active stopping condition located on one side of the center line of the track rails with respect to the normal direction of traffic, car equipment comprising receiving devices located on both sides of the center line of the vehicle, a coil on each of said receiving devices connected in a circuit including a source of uni-directional voltages, a second coil on each of said receiving devices, a circuit including the winding and the front contact of a stick relay and a source of uni-directional voltage, and a reversing switch operated in accordance with the direction of rotation of a car axle for selectively connecting said second coil of one or the other of said receiving devices in series with said circuit in accordance with the direction in which the vehicle is traveling.

5. In an automatic train control system, the combination with a stretch of track having traffic controlled influence communicating devices on one side of the center line of the track rails with respect to the normal direction of traffic, car equipment comprising receiving devices located on both sides of the center line of the vehicle, a coil on each of said receiving devices, a circuit including the winding and the front contact of a stick relay and a source of uni-directional voltage, and a reversing switch frictionally operated in accordance with the direction of rotation of a car axle, for selectively connecting the coil of one or the other of said receiving devices in series with said circuit in accordance with the direction in which the vehicle is traveling, said reversing switch including means for preventing the opening of said circuit when such change of coils in said circuit is effected.

6. In an automatic train control system, the combination with a stretch of railway track having two groups of signals for governing traffic in both directions, two groups of track influence communicating devices governed in accordance with the indications of said groups of signals respectively, said groups of communicating devices being located on opposite sides of the center line of the track rails, car equipment comprising, a normally energized control relay of the stick type, a stick circuit including said relay, a source of uni-directional voltage and a front contact of said relay, influence receiving devices on opposite sides of the center line of the vehicle, means automatically operated for alternately connecting said stick circuit to one and then the other of said devices as the direction of movement of the vehicle is reversed, whereby the influence receiving device connected in said stick circuit is influenced by the group of communicating devices governed by the group of signals which controls traffic in the direction in which the vehicle is traveling, a normally energized repeater relay controlled by said control relay, and manually operable means for closing a pick-up circuit for said control relay upon the de-energization of said repeater relay.

double track meeting points, two groups of signals in said single track territory, each group governing traffic in one direction, each group of signals giving the usual clear, caution and danger indications to a train traveling in one direction due to traffic ahead in the same direction, and giving a stop indication to said train due to a train ahead traveling in the opposite direction, two groups of trackway influence communicating devices governed respectively by said groups of signals and comprising inert non-magnetized iron bodies when in their active stopping condition, car equipment comprising receiving devices located on both sides of the center line of the vehicle, a coil on each of said receiving devices, a circuit including the winding and front contacts of a stick relay and a source of uni-directional voltage, and a reversing switch, operated in accordance with the direction of rotation of a car axle, for selectively connecting the coil on one or the other of said receiving devices in series with said circuit in accordance with the direction in which the vehicle is traveling, whereby said stick relay is governed by the influences from said group of trackway communicating devices which is controlled in accordance with traffic conditions ahead in the direction of movement of the vehicle in single track or double track 70 75 80 85 90 95

7. In an automatic train control system, the combination with a stretch of railway track having two groups of signals for governing traffic in both directions, two groups of track influence communicating devices governed in accordance with the indications of said groups of signals respectively, said groups of communicating devices being located on opposite sides of the center line of the track rails, car equipment comprising, a normally energized control relay of the stick type, a stick circuit including said relay, a source of uni-directional voltage and a front contact of said relay, influence receiving devices on opposite sides of the center line of the vehicle, means automatically operated for alternately connecting said stick circuit to one and then the other of said devices as the direction of movement of the vehicle is reversed, whereby the influence receiving device connected in said stick circuit is influenced by the group of communicating devices governed by the group of signals which controls traffic in the direction in which the vehicle is traveling, a normally energized train control device governed by said control relay and active to cause an automatic brake application when de-energized, and manually operable means effective for a predetermined time only for maintaining said train control device energized irrespective of said relay and for again picking up said relay.

35 the vehicle in single track or double track territory irrespective of which end of the vehicle is leading.

9. In a train control system, the combination with car equipment for train control system, comprising, an impulse receiving device on each side of the car which has an exciting coil and a receiving coil, a normally energized relay, and automatic means dependent for its operation upon the reversal of the direction of rotation of the car axle including a friction device for alternately connecting said receiving coils to the relay as the car changes its direction of movement relative to the trackway.

10. In a train control system, the combination with car equipment comprising duplicate impulse receiving elements on opposite sides thereof, each comprising a normally energized exciting coil and a receiving coil, normally energized translating means on the car maintained energized by one of said impulse elements, and automatic make-before-break means for alternately connecting the receiving coils to said translating means dependent upon the direction of movement of the car relative to the trackway.

11. In a train control system, in combination with a single track railway having double track meeting points, two groups of signals in said single track territory, each group governing traffic in one direction, each group of signals giving the usual clear, caution and danger indications to a train

8. In a train control system, in combination with a single track railway having 130 caution and danger indications to a train traveling in one direction due to traffic ahead

- in the same direction, and giving a stop indication to said train due to a train ahead traveling in the opposite direction, two groups of trackway influence communicating devices governed respectively by said groups of signals and comprising inert non-magnetized iron bodies when in their active stopping condition, car equipment comprising receiving devices located on both sides 5 of the center line of the vehicle, a coil on each of said receiving devices connected in a circuit including a source of unidirectional voltage, a second coil on each of said receiving devices, a circuit including the winding and the front contact of a stick relay and a source of uni-directional voltage, and a reversing switch, operated in accordance with the direction of rotation of a car axle, for selectively connecting said second coil of 10 one or the other of said receiving devices in series with said circuit in accordance with the direction in which the vehicle is traveling, whereby said stick relay is governed by the influences from said group of trackway communicating devices which is controlled in accordance with traffic conditions ahead in the direction of movement of the vehicle in single or double track territory, irrespective of which end of the vehicle is leading.
12. In a train control system, the combination with a stretch of single track having signals for governing traffic in both directions, a track influenced device at each signal governed by the signal in accordance with 15 the indication thereof, and car equipment comprising duplicate receiving means on opposite sides of the car adapted to be influenced by said track devices, the receiving means on the side of the car which corresponds to the track device governing traffic in the direction in which the car is then traveling being active and the other inactive, and during change of direction of movement of the car at least one of the receiving means 20 being active.
13. In a train control system, the combination with a stretch of single track having signals for governing traffic in both directions, a track influenced device at each signal governed in accordance with the indication thereof, and car equipment comprising duplicate receiving means on opposite sides of the car adapted to be influenced by said track influenced devices, and automatic 25 means operated in accordance with the direction of rotation of the car axle and including a friction device for rendering effective the receiving means on the side of the car corresponding to those track devices for governing traffic in the direction in which the car is then traveling.
14. In a train control system, the combination with an absolute-permissive-block signal system including fixed semaphore signals 30 and having trackway influence devices at each signal governed by the signals and in accordance with the indication of that signal, influence devices carried on the car on opposite sides thereof, and automatically placed in condition to cooperate with the track devices governing traffic in the direction in which the car is then traveling.
15. In a train control system, the combination with a car equipment having duplicate inductive impulse receiving means on the car which are alternately rendered effective dependent upon the direction of movement of the car relative to the trackway for maintaining a stick relay energized under safe traffic conditions regardless of the direction of travel of the vehicle, of stretches of track signalled for one direction, and stretches of track signalled for both directions, each stretch being equipped with inductive impulses transmitting track devices located on the same side of the track with respect to the direction of traffic governed by the signals.
16. In a train control system, the combination with a single track railway having double track meeting points, two groups of signals each group governing traffic in one direction, each group of signals giving the usual clear caution and danger indications due to traffic ahead in the same block or in the next block in advance traveling in the same direction, and giving a stop indication due to a train ahead moving in the opposite direction, trackway devices governed by said signals, car equipment adapted to regulate the movement thereof on either double track or single track and automatically modified to provide proper control corresponding to the direction of the movement of the car and irrespective of which end is ahead.
17. In an automatic train control system, the combination with an absolute-permissive-block signal system including fixed signals each governed in accordance with the traffic moving in one direction in two successive blocks and the traffic moving in the opposite direction in a series of blocks, trackway devices at each signal governed by said signal and located distinctively with respect to the track dependent upon the direction of movement governed by the signal in accordance with which the trackway device is governed, and influence devices carried on the car on opposite sides thereof and automatically placed in condition to cooperate with the track devices governing traffic in the direction in which the car is then traveling.
18. In a train control system, the combination with a stretch of single track having signals for governing traffic in both directions, a track influence device at each signal governed in accordance with the indication thereof, and car equipment comprising du-

- plicate receiving means on opposite sides of the car adapted to be influenced by said track devices, and means automatically actuated by the rotation of a car axle through 5 an intervening friction driven device for rendering effective the receiving means on the side of the car corresponding to the track device governing traffic in the direction in which the car is then traveling.
- 10 19. In an automatic train control system, the combination with vehicle carried elements located on opposite sides of a vehicle each having depending legs terminating in a plane a predetermined distance above the 15 track and crossing rails, a secondary coil on one of the legs of said elements, a control relay, means governed automatically in accordance with the direction of movement of the vehicle for connecting said control relay to one or the other of said elements, a trackway element comprising an inert mass of iron when in its active condition and located on a predetermined side of the track corresponding to the direction of traffic it is 20 25 to govern for inducing a voltage in said secondary coil, said trackway element having upstanding legs terminating in a plane above the top of the track rails and adapted to cooperate with the effective vehicle carried element if the vehicle is traveling in the proper direction, and train control mechanism controlled by said relay.
20. An automatic train control system comprising, car-carried elements located on opposite sides of the center line of a railway vehicle each having a secondary receiving coil, a control relay, means governed automatically from the axle of the vehicle for connecting said relay to one or the other 30 35 of said elements depending on the direction of movement of the vehicle, a train control device governed by said relay, means manually operable by the engineer for preventing said train control device from being initiated, and means for recording the operation of said manually operable means.
21. In an automatic train control system, the combination with a brake control apparatus on a vehicle, normally energized control means on the vehicle for initiating operation of said apparatus, said control means if momentarily deenergized remaining deenergized until restored, influence communicating means located on opposite sides of the vehicle, means automatically operated in accordance with the direction of movement of the vehicle for connecting said control means to one or the other of said influence communicating means, manually operable 40 45 means on the vehicle adapted to maintain said brake control apparatus inactive independently of the control thereof by said control means providing the manually operable means is operated prior to the initiation 50 55 of the operation of said control means, and means for restoring said control means effective if said control means is deenergized while said manually operable means is operated. 70
22. An automatic train control system according to the preceding claim, further characterized by the provision of means to penalize the engineer if the manually operable means is moved to its effective position for more than a predetermined interval of time. 75
23. Car-carried equipment for automatic train control systems comprising, a relay having a stick circuit including a front contact thereof, an influence receiving device located on each side of the vehicle, means frictionally operated in accordance with the direction of movement of the vehicle for connecting the stick circuit of said relay directly to a corresponding influence receiving device, said means being constructed so that 80 85 the stick circuit will not be interrupted when a change of connection from one influence communicating device to the other is made. 85
24. Car-carried equipment for automatic train control systems comprising, a circuit including a source of energy, a relay and a front contact of said relay, an influence receiving element on each side of the vehicle, means frictionally operated in accordance 90 95 with the direction the vehicle is traveling and including a make-before-break contact for alternately connecting one or the other of said influence communicating devices directly in said circuit in overlapped relation 100 as the direction of movement of the vehicle is reversed, whereby the circuit will not be interrupted during the reversal of the direction of movement of the vehicle. 100
25. Car equipment for automatic train control systems comprising, an influence receiving element on each side of the vehicle each including a normally energized primary winding and a secondary winding, a brake control device connected in circuit 105 110 with said primary windings, a normally energized control relay connected in a stick circuit including a source of energy and a front contact of said relay, and make-before-break circuit controlling means frictionally operated for alternately connecting said stick circuit directly to one and then the other of said secondary windings as the direction of movement of the vehicle is reversed. 115 120
26. Car equipment for automatic train control systems comprising, a normally energized control relay of the stick type, a stick circuit including said relay, a source of energy and a front contact of said relay, influence receiving devices on opposite sides of the vehicle, means automatically operated for alternately connecting said stick circuit to one and then the other of said devices as 125 130 the direction of movement of the vehicle is

reversed, a normally energized repeater relay controlled by said control relay, and manually operable means for closing a pick-up circuit for said control relay upon de-energization of said repeater relay.

27. Car equipment for automatic train control systems comprising, a normally energized control relay of the stick type, a circuit including said relay, a source of energy

- 10 and a front contact of said relay, influence receiving devices on opposite sides of the vehicle, means automatically operated for alternately connecting said circuit to one and then the other of said devices as the direction of movement of the vehicle is reversed, a normally energized train control device governed by said control relay, and manually operable means effective for a predetermined time only for maintaining said
- 15 train control device energized irrespective of said relay and for again picking up said relay.

28. An automatic train control system comprising, inductive influence transmitting

- 25 means governed in accordance with traffic conditions ahead of a vehicle moving in a certain direction including the rails of the trackway, car equipment comprising a receiving element mounted to be effective
- 30 when the vehicle moves in one direction and another element effective when the vehicle moves in the other direction, a normally energized control relay having a stick circuit which is maintained energized
- 35 if connected to one or the other of said elements under predetermined traffic conditions, and make-before-break circuit controlling means automatically shifted by frictionally operated means responsive to a
- 40 change in the direction of travel of the vehicle for shifting said stick circuit for said control relay from one element to the other without interrupting the flow of current through said stick circuit during such shifting operation.

29. In a train control system, the combination with a stretch of track having traffic controlled influence devices on one side of the track with respect to the normal direction of traffic, car equipment comprising a

- 50 receiving element on each side of the car adapted to be influenced inductively from the trackway through an intervening air gap, and automatic means including a friction device responsive to the direction of rotation of the car axle and having limiting stops for rendering said elements alternately effective.

- 55 30. An automatic train control system comprising, a brake applying means acting on the usual air brake system, automatically actuated control means for governing said brake applying means, means on the vehicle for preventing the actuation of said control means and effective only if actuated

before said brake applying means has been initiated, means for recording the actuation of said last mentioned means, and means only accessible from the ground for resetting said control means to normal, said resetting means, so long as maintained in the resetting condition, causing an operation of said brake applying means.

31. In an automatic train control system, in combination with a stretch of single track

75 having two groups of wayside signals for governing traffic in each direction respectively, each group of signals giving the usual clear, caution and danger indications to a given train due to a train in advance moving

80 in the same direction as said given train, and giving a stop indication to said given train due to a train in advance moving in the opposite direction to said given train, two

85 groups of inductive trackway influence communicating devices located on opposite sides of the center line of the track rails and governed respectively by said groups of signals

90 in accordance with the indications thereof, said trackway influence communicating devices comprising inert non-magnetized, magnetic bodies when in their active stopping condition, car equipment comprising two inductive receiving devices located on opposite

95 sides of the center line of the vehicle respectively, each of said receiving devices having a primary coil and a secondary coil, a circuit including a source of uni-directional potential connected in series with the primary coils of both of said receiving devices, a

100 stick circuit including a source of uni-directional potential and the winding and front contact of a stick relay, an automatic reversing switch operated in accordance with the direction in which the vehicle is travel-

105 ing for selectively connecting said secondary coil of one or the other of said receiving devices in series with said stick circuit, whereby said stick relay is controlled in accordance

110 with traffic conditions ahead irrespective of which end of the vehicle is leading, a normally energized repeater relay controlled by said stick relay, and manually operable means for closing a pick-up circuit for said stick relay upon the de-energization of said repeater relay.

32. In an automatic train control system, in combination with a stretch of single track having two groups of wayside signals for governing traffic in each direction

115 respectively, each group of signals giving the usual clear, caution and danger indications to a given train due to a train in advance moving in the same direction as said given train, and giving a stop indication to said given train due to a train in advance moving in the opposite direction to said given train, two groups of inductive trackway influence communicating devices located

120 on opposite sides of the center line of the vehicle

125 respectively, each group of signals giving the usual clear, caution and danger indications to a given train due to a train in advance moving in the same direction as said given train, and giving a stop indication to said given train due to a train in advance moving in the opposite direction to said given train, two groups of inductive trackway influence communicating devices located

130 on opposite sides of the center line of the vehicle

track rails and governed respectively by said groups of signals in accordance with the indications thereof, said trackway influence communicating devices comprising inert non-magnetized, magnetic bodies when in their active stopping condition, car equipment comprising two inductive receiving devices located on opposite sides of the center line of the vehicle respectively, each of said receiving devices having a primary coil and a secondary coil, a circuit including a source of uni-directional potential connected in series with the primary coils of both of said receiving devices, a stick circuit including a source of uni-directional potential and the winding and front contact of a stick relay, an automatic reversing switch operated in accordance with the direction in which the vehicle is traveling for selectively connecting said secondary coil of one or the other of said receiving devices in series with said stick circuit, whereby said stick relay is controlled in accordance with traffic conditions ahead irrespective of which end of the vehicle is leading, a normally energized train control device governed by said stick relay and active to initiate an automatic brake application when deenergized, manually operable means effective for a predetermined time only for maintaining said train control device energized irrespective of the de-energization of said stick relay, and means for causing the de-energization of said train control device irrespective of the operation of said manually operable means if said circuit including the primary coils of said receiving devices is de-energized.

In testimony whereof I hereby affix my signature.

WINTHROP K. HOWE.
